HYDROCARBON CONVERSION PROCESS

Frederick E. Frey, Bartlesville, Okla., assignor to
Phillips Petroleum Company, a corporation of
Delaware

Application October 7, 1940, Serial No. 360,163

7 Claims. (Cl. 260--683.4)

This invention relates to the conversion of light hydrocarbons to form valuable motor fuel stocks. More particularly it relates to a cooperative combination of process steps for producing predominantly aliphatic hydrocarbons in the motor fuel boiling range. It relates more particularly to converting mixtures of hydrocarbons containing hydrocarbons having at least two and not more than five carbon atoms per molecule.

Many processes have been proposed for converting normally gaseous hydrocarbons into hydrocarbons having higher molecular weights, such as motor fuels and lubricants. Some of these processes are dependent upon the presence of large proportions of olefins in the charge stock, as in well known thermal or catalytic polymerization processes for producing motor fuel from refinery gases containing unsaturated components from cracking stills. Still other processes are adapted to produce motor fuel from normally gaseous paraffins, such as unitary thermal conversion processes, multistage processes employing a dehydrogenation step as a first part of the process, followed by a polymerization of the light olefins so produced, or by thermal conversion processes in which there is a concomitant polymerization of gaseous hydrocarbons and reversion of light liquid hydrocarbons. Still other processes have been proposed wherein a paraffinic hydrocarbon stream and an olefinic hydrocarbon stream are charged to a system, and the paraffins and olefins are caused to interreact, or as it is generally stated, the paraffins are alkylated by the olefins to form paraffins having higher molecular weights.

Although both thermal and catalytic olefin polymerization processes can be operated to produce, from normally gaseous olefins, liquid hydrocarbons in the motor fuel boiling range, such as a gasoline stock, I have found that the thermal processes produce a composite motor fuel product having generally a higher volatility than the composite motor fuel product produced by catalytic polymerization from a similar charge stock. This is especially true when the thermal conversion process is operated at a high superatmospheric pressure to produce predominantly aliphatic hydrocarbons in the gasoline boiling range. While in many instances this is an advantage, it is a disadvantage where large volumes of natural gasoline are likewise available and it is desired to produce a composite gasoline containing natural gasoline and such polymer gasoline.

I have now found that, when the effluent of a high pressure thermal conversion process which includes the treatment of normally gaseous hydrocarbons, or a selected portion of such effluent containing both normally gaseous and normally liquid hydrocarbons, is subjected to treatment at moderate temperatures and pressures by intimate

admixture with concentrated sulfuric acid, a very desirable motor fuel stock can be produced which has a moderate, or low, volatility and which has a good antiknock rating. Furthermore, in so treating such a hydrocarbon mixture, in a manner such as will be more fully hereinafter described, I have found that there is an appreciable decrease in the unsaturate content of the total motor fuel boiling range hydrocarbon product without an attendant large loss of hydrocarbon material from this boiling range, such as has been experienced in the past from treatment of an unsaturate-containing motor fuel or motor fuel stock with sulfuric acid to remove sulfur compounds and gum and color-forming bodies, and the like. While the exact reason for this is not known, I believe that, at least in part, it is due to the fact that high pressure thermal conversion of light hydrocarbons produces substantial proportions of low boiling, normally liquid isoparaffin hydrocarbons, and that the low boiling olefins present in the thermal conversion effluent which is treated in the second part of my process unite with these low-boiling isoparaffins to form other paraffin hydrocarbons which are higher boiling but still within the motor fuel boiling range and which have good antiknock ratings. This effect is probably especially predominant in those modifications of my process which include, as the thermal conversion step, a thermal alkylation step such as I have described in my U. S. Patent 2,002,394 and 2,104,296, and in my copending application Serial No. 82,954, now Patent 2,270,700 granted January 20, 1942, and in the patent of Frey and Hepp, 2,209,450, together with copending divisions thereof, and it is a specific modification of my invention to subject normally gaseous paraffin and olefin hydrocarbons to conditions suitable for thermal alkylation, and subsequently to treat at least a portion of the effluent, comprising both normally gaseous and liquid hydrocarbons, with concentrated sulfuric acid, as will be described.

It is to be understood, of course, that normally liquid hydrocarbon products produced by high pressure thermal conversion and in the motor fuel boiling range, or even in the lower part of this range, will not be entirely aliphatic, and that a relatively small amount of the hydrocarbons will be of a cyclic nature and will combine with olefin hydrocarbons to produce alkyl derivatives. Such minor compounds and reactions do not detract in any appreciable manner from the efficiency of my process, and while such reactions may in fact contribute to the total desirable result, it is not believed that these are the principal or predominant reactions. In any event, it will be noted in the following, more detailed description of one modification of my invention, that the entire hydrocarbon material charged to the sul-

furic acid reaction, or alkylation, step is derived from the preceding high pressure thermal conversion step, and this is a feature of my invention.

It is an object of my invention to produce normally liquid hydrocarbons in the motor fuel boiling range from hydrocarbon mixtures containing normally gaseous hydrocarbons.

It is a further object of this invention to submit normally gaseous hydrocarbons to thermal conversion under high pressures to produce normally liquid hydrocarbons having a relatively high volatility, and subsequently in a second process step to produce from the effluent of such a conversion a hydrocarbon motor fuel stock having a lower volatility.

Other objects, and advantages, of my invention will become apparent from the accompanying disclosure and discussion.

A modification of my invention will now be described in connection with the accompanying drawing, which forms a part of this specification and which shows diagrammatically, one arrangement of apparatus for practicing my invention for the production of motor fuel from gaseous hydrocarbons.

A normally gaseous mixture of hydrocarbons having not less than two nor more than five carbon atoms per molecule, and which may be entirely paraffinic such as the lighter portions of raw natural gasoline, or which may contain unsaturates as well, especially olefins, such as a C₃—C₄ fraction from refinery vapors, is introduced to the system through a pipe 10 and valve 11 to a pump 12. This stream will preferably be in liquid phase, so as to be more easily handled. The pump 12 increases the pressure on the stream to one suitable for a subsequent thermal conversion, which will generally be between 500 and 10,000 pounds per square inch, more preferably between 1,000 and 5,000 pounds. The stream then passes to a heating and reacting zone 13, which will be located in any suitable furnace, or similar apparatus, 14, wherein the hydrocarbons are heated to a conversion temperature between 750 and 1200° F., and maintained at a conversion temperature and pressure for a time sufficient to form an optimum yield of normally liquid, predominantly aliphatic hydrocarbons in the motor fuel boiling range. The effluent of the zone 13 passes through a cooler 15, and through pipe 16 and valve 17 to the separating means, represented by the fractionator 20 provided with a heating coil 21 at the bottom and a cooling coil 22 at the top. If it is desired to treat all of the effluent hydrocarbon stream in the subsequent acid alkylation step, the stream may be passed from pipe 16 through pipe 24 and valve 25 to the pump and mixing apparatus 26, for the treatment to be subsequently discussed. Generally, however, it will be more desirable to remove first some of the heavier material and/or some of the lighter gases, as will be more fully hereinafter discussed.

The conversion which takes place in the heating and reacting zone 13 may be any one of the several known methods for the thermal, non-catalytic conversion of normally gaseous hydrocarbons to predominantly aliphatic normally liquid hydrocarbons. If the charge stock is substantially entirely paraffinic, the heating part of zone 13 should be at a temperature of over 1000° F. to form a sufficient amount of unsaturates for subsequent reaction, which may take place at a somewhat lower temperature. If the charge stock includes refinery vapors with a substantial content of unsaturates, the heating part of the zone

should be at a considerably lower temperature so that the mixture is heated only to a temperature sufficient to initiate a subsequent polymerization reaction involving the unsaturates.

As a modification which is especially applicable when two separate charge stocks are available, one substantially entirely paraffinic and the other containing an appreciable amount of unsaturates, the thermal conversion may be one of alkylation such as disclosed in my U. S. patents, 2,002,394 or 2,104,296, or my copending application Serial No. 82,954, now Patent 2,270,700. In such a modification the unsaturate-containing stream of hydrocarbons, such as a mixture having olefins of two to five carbon atoms per molecule is introduced through pipe 30 and valve 31, and is passed at a suitable elevated pressure, in the range previously discussed, by pump 32 to manifold 33 and through a plurality of pipes, such as pipes 34, 35, and 36 supplied with valves 37, 38, and 39 respectively, to the reaction zone 13 wherein a reaction takes place involving a union of olefin and paraffin hydrocarbons, forming a liquid product predominantly aliphatic and paraffinic, but which will of course contain some unsaturated hydrocarbons. It is, of course, understood that this showing is only diagrammatic, and other process arrangements, previously disclosed and discussed, may be used.

As another modification, the reaction zone 13 may be utilized for so called "gas reversion," wherein motor fuel range hydrocarbons having an undesirably low octane number may be reformed in the presence of lighter hydrocarbons. In such a modification, the charge stock entering through pipe 10 will contain such liquid hydrocarbons.

It is generally preferable to separate the heavier material formed, which may include the heavier portion of the motor fuel boiling range hydrocarbons, and also the lighter material formed, such as hydrogen, methane, and ethane, from the effluent of the thermal conversion, and to pass only the intermediate portion of the effluent, such as hydrocarbons having three to twelve carbon atoms per molecule, more preferably three to six or eight carbon atoms per molecule, to the subsequent acid alkylation step. The heavier material may be separated in the means 20 and is removed through pipe 44, and may be removed from the system through valve 45. If the separating means 20 is so operated that this stream contains an appreciable portion of hydrocarbons in the motor fuel boiling range, the stream may be passed from pipe 44 through pipe 46 and valve 47 to separating means such as the fractionator 50 provided with a heating coil 51 at the bottom and cooling coil 52 at the top which can provide liquid reflux. The material too heavy for use is removed through pipe 53 and valve 54, and hydrocarbons in the motor fuel range are removed through pipe 55 and valve 56, it being understood that suitable conventional cooling and condensing equipment is included to make the stream passing through valve 56 a liquid if such is desired.

Hydrocarbons in lower boiling part of the gasoline range, along with lighter hydrocarbons, are removed from the means 20 through pipe 57 and valve 58, and may be passed through valve 59 to separating means such as the fractionating column 60, provided with a heating coil 61 at the bottom and cooling coil 62 at the top. Hydrocarbons having at least three carbon atoms per molecule are passed from fractionator 60 through pipe 63 and valve 64 to pipe 24, and lighter mate-

rial is removed from the system through pipe 65 and valve 66.

In case only lighter material is to be removed from the effluent of zone 13, the effluent stream may be passed from pipe 16 through pipe 67 and valve 68 to pipe 57 and on to fractionator 60. In case only heavier material is to be removed from the effluent of zone 13, the stream passing from fractionator 20 through pipe 57 and valve 58 may be passed from pipe 57 through pipe 70 and valve 71 to pipe 24, as will be appreciated. In following any alternative procedure, it is of course understood that unused apparatus is to be isolated or not included, by suitable use of valves shown, as is obvious.

The hydrocarbon stream flowing through pipe 24 to pump 26 will comprise hydrocarbons having at least three and not more than twelve carbon atoms per molecule, and may or may not contain lighter and/or heavier material as has been discussed, and is treated by being intimately admixed with a suitable quantity of concentrated sulfuric acid. The sulfuric acid is added through pipe 75 and valve 76 to pipe 24 directly ahead of pump 26, and becomes intimately admixed with the hydrocarbon stream, which is preferably in the liquid phase. The intimate mixture, or emulsion, passes through pipe 77 to the alkylator 78, and from the alkylator 78 through pipe 78 and valve 80 to the separating means 81. The alkylator 78 may comprise a long tube coil through which the stream passes with considerable turbulence, from which the heat of reaction may be readily extracted and which may be provided with baffles, orifices, additional pumps or mixers, to insure an adequate prolonged intimate admixture of the sulfuric acid and the hydrocarbon material. Light olefins having at least three carbon atoms per molecule, or polymers of such light olefins such as triisobutylene, or tetra-isobutylene, and/or light isoparaffins such as isobutane, isopentane and the like, may be added to pipe 24 and to this second part of the process through pipe 72 and valve 73, when desired.

In separating means 81 a separation is effected between the sulfuric acid and the hydrocarbon material, and the sulfuric acid is removed through pipe 82, and may be discharged from the system through valve 83. Any part, or all, of this sulfuric acid stream may be recirculated through pipe 84 and valve 85 to pipe 75, and generally a portion of the stream will be so circulated, the remainder being withdrawn through valve 83 for purification and reclamation before being reintroduced to the system through pipe 75. The separating means 81 may also include means for separating and/or neutralizing the free acid, acidic products, and esters, etc., which may be present in the hydrocarbon fraction, which is removed from separating means 81 through pipe 86 and valve 87 to a separating system represented by fractionator 90. Such neutralization and separation will involve additional apparatus, not shown in detail, which may be understood to be included as a part of the separating means 81.

The hydrocarbon effluent from the alkylator 78 is separated in fractionator 90 into a normally gaseous fraction and a normally liquid fraction, the fractionation being aided by heating coil 91 and cooling coil 92. The normally liquid hydrocarbon fraction is removed through pipe 93, and may be discharged from the system through valve 94. Any part, or all, of this stream may be diverted from pipe 93 through pipe 95 to be blended, as desired, with normally liquid hydrocarbons pro-

duced by the thermal conversion. This may be done, and at the same time the heavier hydrocarbons removed from this stream, by passing it from pipe 93 through pipe 95 and valve 96 to pipe 46 and on into fractionator 50, or the stream may be added directly to the stream in pipe 55 by passing from pipe 95 through pipe 97 and valve 98. Under certain conditions of operation, of course, the hydrocarbons passing from fractionator 90 through pipes 93 and 95 will be the only material treated in fractionator 50.

Any low boiling material present in the effluent of the acid alkylation, and especially methane and hydrogen, may be removed from the top of fractionator 90, and from the system, through pipe 100 and valve 101. All of the low boiling material which is not desired for inclusion in motor fuel may be removed in this manner, but generally low boiling hydrocarbons having at least two carbon atoms per molecule, and especially C₃ and C₄ hydrocarbons, are advantageously treated in the thermal conversion part of the process. Such normally gaseous hydrocarbons may be removed from an upper point of the fractionator 90 through pipe 102 and valve 103, and may be passed directly to pipe 10, for treatment in the reaction zone 13, through pipe 104 and valve 105.

No matter what particular type of thermal conversion is carried out in the heating and reaction zone 13, the light hydrocarbon mixture passing through pipe 102 will be substantially free of any unsaturated hydrocarbons and will be predominantly paraffinic. In order to fit in most advantageously with the high-pressure conversion in zone 13, it may at times be more desirable to recycle a light hydrocarbon mixture which contains an appreciable portion of light unsaturated hydrocarbons, predominantly or entirely olefins. To this end, hydrocarbons passing through pipe 102 may be subjected to low pressure dehydrogenation, either catalytic or thermal, before being passed to the high pressure conversion step. This may be accomplished by passing all or a part of the stream from pipe 102 through pipe 106 and valve 107 to dehydrogenation equipment represented by the thermal dehydrogenation coil 110 in furnace 111. The dehydrogenation should be carried out at a pressure not in excess of about 200 pounds per square inch and at a temperature between 750 and 1550° F., with a relatively short reaction time, to produce an optimum yield of normally gaseous unsaturated hydrocarbons with very little, if any, production of normally liquid hydrocarbons. As will be obvious to those skilled in the art, catalytic dehydrogenation with known catalysts, such as chromium oxide gel, bauxite, or other synthetic or natural materials, may be employed with similar although not completely equivalent results, under known conditions for such catalysts.

The dehydrogenation effluent is preferably passed through pipe 112 and valve 113 to separating means such as the fractionator 120, although if desired, it may be passed directly to the high pressure conversion step, from pipe 112 through pipe 115 and valve 116 to pipes 104 and 10. The fractionator 120 is equipped with a heating coil 121 and a cooling coil 122. Light gases such as hydrogen and methane are removed and discharged from the system through pipe 123 and valve 124. If it is desired to retain ethylene and discard ethane, some kind of selective absorption equipment, or the like, may be included, although such is not shown. Any undesired normally liquid

hydrocarbons, or tar, may be removed through pipe 125 and valve 126. A normally gaseous hydrocarbon fraction, containing unsaturated hydrocarbons and suitable for high pressure thermal conversion, is removed through pipe 127 and valve 128, and is passed through pipes 104 and 10 to the reaction zone 13. If desired, a portion or all of this stream may be passed from pipe 127 through pipe 130 and valve 131 to pipe 30 for subsequent introduction into the zone 13 as has been described. When the thermal conversion step is one of thermal alkylation, the hydrocarbon stream passing through pipe 102 may be further fractionated into a light and a heavier fraction. The light fraction only is then dehydrogenated, while the heavier fraction is passed directly to the pipe 10. The olefins produced by the dehydrogenation are then passed to pipe 30.

When paraffin hydrocarbons are charged to the process, it may at times be found desirable to subject them to dehydrogenation before they are subjected to high pressure conversion. In such a case, all or a part of the paraffin hydrocarbons may be introduced to the system through pipe 117 and valve 118, passing through pipe 106 to the dehydrogenation, as has been described.

If desired, heavy unsaturated hydrocarbons removed through valve 45 or valve 54, or some part of such hydrocarbons, may be passed to the acid alkylation step, and can be introduced through pipe 72 if desired. Hydrogen will be present in small quantities in the light gases passed from the system through pipe 65, and in considerable quantities in the light gases removed through pipe 123. This hydrogen, especially that recovered through pipe 123, is quite suitable for hydrogenation, either destructive or nondestructive, and although it may be desirable to purify or concentrate it, it may be used without such treatment since substantially the only impurities are relatively light, inert hydrocarbons. It may be used for the non-destructive hydrogenation of unsaturated hydrocarbons produced by the high pressure conversion, or for destructive hydrogenation of the before mentioned heavy unsaturated material.

The high pressure thermal conversion step of my process broadly includes any such process operating under a pressure in excess of 500 pounds per square inch, and preferably in excess of 1000 pounds per square inch. Such pressures may run as high as 10,000 to 15,000 pounds per square inch or more depending somewhat on the strength of the apparatus, although generally pressures up to 5,000 pounds per square inch will be sufficient. In general, the temperatures will be between 750 and 1200° F., preferably 900 to 1100° F., and catalysts will not be used except as the materials of the apparatus used may have an inherent fortuitous catalytic activity. The charge stock to this thermal conversion step should contain only little, if any, methane, and while some pentanes or pentenes may be included in normally gaseous mixtures, large amounts of such material will generally not be treated. The charge stock may be entirely paraffinic, or may contain unsaturated hydrocarbons, especially olefins, and in some cases may comprise two separate hydrocarbon streams, one paraffinic and one unsaturated. In those cases where only a paraffinic hydrocarbon mixture is available, and it is desired to have some unsaturated hydrocarbons present in the charge stock a dehydrogenation step may be included in the process, as has been described. Such a dehydrogenation step may be

entirely thermal, or it may be catalytic, or it may involve a combination of thermal and catalytic steps, under known conditions.

It is a characteristic of thermal hydrocarbon synthesis, when conducted under high pressures and other conditions which I contemplate, that ethylene is particularly readily converted. This results in a reaction effluent which usually has a low ethylene content but which has appreciable concentrations of higher olefins. No gaseous components in the effluent are inherently unsuitable for inclusion in the acid alkylation feed stock, except as the lightest constituents may be somewhat of a nuisance because of a tendency for them to promote the formation of excessive amounts of a gas phase.

The entire effluent of the high pressure thermal conversion step may be passed without separation to the subsequent sulfuric acid alkylation step. In many cases, however, it will be found more desirable to separate from the effluent, as a charge stock, a hydrocarbon fraction which is substantially free from material lower boiling than C₃ hydrocarbons and/or also substantially free from material boiling above the motor fuel range. In many cases it will also be desirable to have such a fraction free from hydrocarbons boiling in the upper part of the motor fuel range, such as C₁₂ and heavier hydrocarbons, and at times hydrocarbons having as few as seven or eight carbon atoms per molecule may be advantageously removed. In any event, both normally gaseous hydrocarbons and normally liquid hydrocarbons present in the effluent of the high pressure step will be in the charge to the sulfuric acid alkylation step. While it will generally be desirable to incorporate substantially all the C₃ hydrocarbon fraction in the charge stock to the acid alkylation step, in order to obtain full benefit of the propylene present therein. If the propylene content is too small, however, the C₃ fraction need not be included, and in such a case only hydrocarbons heavier than C₃ will be sent to the acid alkylation step. However, even in this modification, the light hydrocarbons, represented by C₄ hydrocarbons, will generally be present in a relative amount in excess of that normally present in motor fuel. If desired, the olefins may be separated in more concentrated form from these lighter hydrocarbons, and only this light olefin concentrate will then be included with the motor fuel range hydrocarbon portion of charge to the acid alkylation step.

The acid alkylation step should be carried out at a reaction temperature not lower than about 0° F., and generally not higher than about 125° F. A preferred range is between 30 and 75° F. The pressure will generally not need to be in excess of about 200 pounds per square inch gage. It is important that the hydrocarbon material and the sulfuric acid be intimately mixed, and that this intimate mixture be maintained throughout the reaction period, which will generally be between 1 and 30 minutes. The ratio of hydrocarbon material to sulfuric acid, on a weight basis, should be larger than in familiar gum and color treating, should be sufficient to promote effectively the desired alkylation, and will preferably be 5 to 50 per cent by weight of the hydrocarbon stream.

Example I

The following is cited as one example of the operation of my process. A propane-butane mixture from a natural gasoline plant is sub-

jected to thermal conversion at a maximum conversion temperature of about 1090° F. for a total reaction time of about 5 minutes under a pressure of about 2400 pounds per square inch, with a high input of heat during the first part of the conversion, wherein the maximum temperature is reached, and with an abstraction of heat during the latter part of the conversion. The effluent stream is passed to separating means, and separated into the fractions shown in the accompanying table.

Fraction	Percent by weight
Light gas	23.6
Cr-C ₇	66.0
Heavy naphtha	8.7
Heavier than gasoline	1.7
	100.0

The C₃-C₇ fraction, as a liquid, is intimately and continuously mixed with about 25 per cent by weight of 97 per cent sulfuric acid, and is passed to a reaction chamber provided with means for maintaining a continuous agitation of the contents. The mixture is maintained, with removal of heat, at a temperature between 50 and 80° F., for a reaction period between 5 and 15 minutes, and is then passed to a separator to separate the hydrocarbon phase and the acid phase. A portion of the acid phase is recirculated to the reaction zone, and another portion is passed to other equipment, for reclamation. The hydrocarbon phase is neutralized with caustic alkali, and a motor fuel fraction is then separated by fractionation. This motor fuel has very little olefinic material in it, and has an octane number of about 75. The material lower boiling than this motor fuel fraction is passed to the thermal conversion step, by being added to 40

cent of the total, is subjected to sufficient pressure to keep it in the liquid state at 75° F., and is intimately admixed with about 40 per cent by weight of 96 per cent sulfuric acid, at a temperature of about 60° F. This intimate mixture is passed through a tube coil at a high enough velocity to insure turbulent flow, the tube coil being surrounded by water to abstract the heat of reaction, and having a length sufficient to insure a reaction time of about 10 minutes. The hydrocarbons are separated in an acid-free state, and a motor fuel fraction is separated by distillation. This motor fuel fraction contains less than 5 per cent of olefin hydrocarbons, has an excellent volatility and a desirable distillation curve and has an octane number above 80.

The hydrocarbon material lighter than motor fuel may be subjected to further fractionation to produce an isobutane fraction and a lighter fraction. The isobutane fraction may be returned directly to the thermal conversion, while the lighter hydrocarbons, essentially ethane and propane, are then subjected to dehydrogenation, and the resulting light olefins are also passed to this conversion step.

While my invention has been more particularly described in connection with certain specific limitations as being most favorable for a particular modification, it is to be understood that I do not wish to be so limited for all modifications. Other modifications than those specifically described will be within the spirit of the invention and disclosure and will be obvious to those skilled in the art from the teachings presented herewith. Numerous fractionators, reaction zones, and the like have been shown diagrammatically without details of conventional auxiliary equipment. It will be understood that all ordinary equipment can be supplied in detail by one skilled in the art in connection with the installation of any particular modification of my invention which follows the teachings presented herewith, and suitable conditions for operation in specific instances can readily be determined by trial in the light of the specification.

45 I claim:

1. In a process for the production of a predominantly saturated hydrocarbon motor fuel having a low volatility from lighter hydrocarbons, the steps which comprise subjecting a hydrocarbon mixture comprising hydrocarbons having two to five carbon atoms per molecule to a thermal conversion in the absence of a catalyst under a pressure between 500 and 10,000 pounds per square inch at a temperature between 750 and 1200° F. for a period of time to form an optimum yield of aliphatic hydrocarbons in the motor fuel boiling range, separating from the effluent of said conversion a hydrocarbon fraction comprising essentially normally gaseous and normally liquid hydrocarbons having at least three and not more than twelve carbon atoms per molecule and including both olefin and low boiling isoparaffin hydrocarbons, intimately admixing said hydrocarbon fraction with concentrated sulfuric acid in the absence of added isoparaffin hydrocarbons, the amount of sulfuric acid being between about 5 and 50 per cent by weight while maintaining a reaction temperature between 0 and 125° F. and a pressure sufficient to maintain said hydrocarbons substantially in the liquid state, maintaining said intimate admixture for a period of time sufficient to effect an addition of said olefin hydrocarbons to said low-boiling isoparaffin hydrocarbons to form paraffin hydrocarbons having a low volatility and in the motor fuel boiling range, and separating

Example II

The following is cited as another example of the operation of my process. A paraffinic hydrocarbon mixture comprising essentially isobutane was circulated through a tube coil maintained at about 970° F., under a pressure of about 2500 pounds per square inch. An ethylene-containing hydrocarbon mixture was continuously added to the circulating stream, and a portion of the effluent stream was continuously withdrawn. The average reaction time was about 4.3 minutes, and the average composition of the composite charge was about 10 per cent olefin and 90 per cent paraffin. This mode of operation favored a reaction of olefins with paraffins to form paraffins in the motor fuel range, and the effluent had the following composition.

Component	Per cent unsaturates	Per cent by weight
A ₁ and CH ₄	0	3.1
C ₂	29	3.7
C ₃	35	4.8
C ₄	3	75.7
C ₅	25	2.9
C ₆	10	5.7
C ₇	23	1.3
C ₈	32	1.5
Heavy naphtha		0.7
Tar		0.6
	70	100.0

The effluent is freed from the light gases, chiefly methane and ethane, and from the tar. The remainder of the effluent, comprising over 90 per

from the effluent a hydrocarbon fraction comprising hydrocarbons in the motor fuel boiling range.

2. A process for the production of normally liquid hydrocarbons in the motor fuel boiling range from lighter hydrocarbons, which comprises adding to a stream of predominantly paraffinic hydrocarbons having between two and five carbon atoms per molecule, maintained at a conversion temperature and pressure and in the absence of a catalyst, successive small quantities of olefinic hydrocarbons having two to four carbon atoms per molecule in such a manner and in such amounts that predominantly paraffinic hydrocarbons in the motor fuel boiling range are produced including low-boiling isoparaffin hydrocarbons and minor amounts of olefin hydrocarbons, separating from the effluent a hydrocarbon fraction containing hydrocarbons in and below the motor fuel boiling range, intimately admixing with said hydrocarbon fraction in the absence of added isoparaffin hydrocarbons concentrated sulfuric acid under a pressure sufficient to maintain said hydrocarbon fraction in the liquid state and maintaining the mixture at a reaction temperature not in excess of about 125° F. for a period of time sufficient to effect a union of said low-boiling isoparaffin hydrocarbons and said olefin hydrocarbons to form paraffin hydrocarbons having a low volatility and in the motor fuel boiling range, and separating from the resultant mixture a hydrocarbon fraction comprising hydrocarbons in the motor fuel range so produced.

3. In a process for converting normally gaseous hydrocarbons to normally liquid hydrocarbons in the motor fuel boiling range, the steps which comprise subjecting a normally gaseous hydrocarbon mixture, containing not more than 10 per cent by weight of olefins predominantly ethylene with the remainder being paraffin hydrocarbons predominantly isobutane, to a thermal conversion at a pressure in excess of 1000 pounds per square inch and adapted to promote a union of olefin and paraffin hydrocarbons to form paraffin hydrocarbons in the motor fuel boiling range, passing at least that portion of the effluent having three to eight carbon atoms per molecule inclusive and including both olefins and low-boiling isoparaffin hydrocarbons to a sulfuric acid alkylation step, intimately admixing with said portion of the thermal conversion effluent, and in the absence of added isoparaffin hydrocarbons, concentrated sulfuric acid and maintaining said intimate admixture at an alkylation temperature and pressure for a period of time to effect a union of said olefin and said low-boiling isoparaffin hydrocarbons to form an optimum yield of paraffin hydrocarbons in the motor fuel boiling range, and subsequently separating from the effluent a hydrocarbon fraction comprising hydrocarbons in the motor fuel boiling range.

4. A process for converting normally gaseous hydrocarbons to normally liquid hydrocarbons in the gasoline boiling range, which comprises subjecting a normally gaseous hydrocarbon mixture comprised predominantly of isobutane to thermal, noncatalytic treatment under a pressure in excess of 500 pounds per square inch at a temperature within the range of 750 to 1200° F. for a time such that there is an optimum conversion to predominantly aliphatic normally liquid hydrocarbons in the gasoline range, separating from the effluent a hydrocarbon fraction comprising essentially normally gaseous and normally liquid hydrocarbons having at least three and not more than twelve carbon atoms per molecule and in-

cluding both olefin and low-boiling isoparaffin hydrocarbons, intimately admixing said hydrocarbon fraction in the absence of added isoparaffin hydrocarbons with an alkylation quantity of concentrated sulfuric acid while maintaining an alkylation temperature, pressure, and reaction time to effect an alkylation reaction of said olefins and said low-boiling isoparaffin hydrocarbons to form alkylation products in the gasoline boiling range, and separating from the alkylation effluent a hydrocarbon fraction comprising hydrocarbons in the gasoline range so produced.

5. A process for converting a hydrocarbon mixture to form hydrocarbons in the gasoline boiling range, which comprises thermally converting a mixture of hydrocarbons having at least two carbon atoms per molecule and boiling not higher than the end point of gasoline under an elevated superatmospheric pressure and at a conversion temperature and for a time to produce an optimum yield of normally liquid substantially aliphatic hydrocarbons in the gasoline boiling range, passing the effluent to a first separating means, separating therefrom heavier normally liquid hydrocarbons comprising hydrocarbons in the gasoline range and passing same to a second separating means, separating also from said first separating means a hydrocarbon fraction comprising a substantial portion of the effluent of said thermal conversion having three to six carbon atoms per molecule and including both olefin and low-boiling isoparaffin hydrocarbons, intimately admixing said hydrocarbon fraction in the absence of added isoparaffin hydrocarbons with an alkylation quantity of concentrated sulfuric acid while maintaining alkylation conditions of temperature, pressure and reaction time to effect an alkylation reaction of said olefins and said low-boiling isoparaffin hydrocarbons to form alkylation products in the gasoline boiling range, separating from the alkylation effluent a normally liquid hydrocarbon mixture comprising hydrocarbons in the gasoline boiling range, passing said hydrocarbon mixture to said second separating means, and separating therefrom a hydrocarbon mixture in the gasoline boiling range.

6. A process for converting a hydrocarbon mixture to produce hydrocarbons suitable for motor fuel, which comprises thermally converting a mixture of hydrocarbons containing propane and butane and low octane number normally liquid hydrocarbons boiling not higher than the end point of motor fuel under a superatmospheric pressure at a temperature within the range of 750 to 1200° F. for a time such that there is an optimum conversion to normally liquid hydrocarbons in the motor fuel range including low-boiling isoparaffin hydrocarbons, passing at least a portion of the effluent to a separating means, separating therefrom a first hydrocarbon fraction comprising essentially normally gaseous and normally liquid hydrocarbons having at least three and not more than seven carbon atoms per molecule and including both olefin and said low-boiling isoparaffin hydrocarbons, separating also from said separating means a second hydrocarbon fraction comprising essentially normally liquid hydrocarbons in the motor fuel range, intimately admixing said first hydrocarbon fraction in the absence of added isoparaffin hydrocarbons with an alkylation quantity of concentrated sulfuric acid while maintaining alkylation conditions of temperature, pressure and reaction time to effect an alkylation reaction between said olefin and said low-boiling isoparaffin hydrocarbons to form an optimum

yield of hydrocarbons in the motor fuel boiling range, separating from the alkylation effluent a normally liquid hydrocarbon mixture comprising hydrocarbons in the motor fuel boiling range, and blending the last said hydrocarbon mixture with said second hydrocarbon fraction to produce a hydrocarbon mixture suitable for motor fuel.

7. A process for treating a hydrocarbon mixture to produce hydrocarbons suitable for motor fuel, which comprises passing a mixture of hydrocarbons having at least two carbon atoms per molecule and boiling not higher than the end point of motor fuel to a noncatalytic conversion zone under an elevated superatmospheric pressure and at a conversion temperature for a period of time to produce an optimum yield of normally liquid substantially aliphatic hydrocarbons in the motor fuel boiling range including low-boiling isoparaffins, intimately admixing with

5 at least a portion of the effluent from said conversion zone, comprising normally gaseous and normally liquid hydrocarbons and including olefins and said low-boiling isoparaffin hydrocarbons, and in the absence of added isoparaffin hydrocarbons concentrated sulfuric acid at an alkylation temperature and pressure to effect a union of said olefin and said low-boiling isoparaffin hydrocarbons forming hydrocarbons in the motor fuel boiling range, subsequently separating from the effluent a hydrocarbon fraction comprising hydrocarbons suitable for motor fuel and removing said fraction from the process, and separating also a normally gaseous hydrocarbon fraction comprising hydrocarbons having at least two carbon atoms per molecule and introducing at least a portion of said hydrocarbons into said noncatalytic conversion zone.
